UNITED STATES PATENT OFFICE.

CHARLES M. HATCHER, OF SEATTLE, WASHINGTON, ASSIGNEE TO THE NATIONAL HANDIPRINT PRESS COMPANY, OF OAKLAND, CALIFORNIA, A CORPORATION.

PRESS.

1,122,919.

Specification of Letters Patent. Patented Dec. 29, 1914.

Application filed April 21, 1913. Serial No. 762,610.

To all whom it may concern:

Be it known that I, CHARLES M. HATCHER, a citizen of the United States of America, and a resident of the city of Seattle, in the county of King and State of Washington, have invented certain new and useful Improvements in Presses, of which the following is a specification.

My invention relates to printing presses, having more particular reference to hand operated presses of the portable type, and it has for its primary aim to provide a novel construction and arrangement of parts which will operate in an efficient manner to thoroughly ink the type and effect a clear print or impression.

Other objects will be set forth as my description progresses, and those features of construction, arrangements and combinations of parts on which I desire protection, succinctly defined in my annexed claims.

Referring to the accompanying drawings, wherein like characters of reference indicate like parts throughout: Figure 1 is a side elevation of a press embodying my invention, the same being in its operative position. Fig. 2 is a top plan thereof, a portion being in section. Fig. 3 is a side elevation of the press in its inoperative or inking position. Fig. 4 is a fragmentary section along line 4—4 of Fig. 2. Fig. 5 is a cross-section of the chase taken on line 5—5 of Fig. 2, and Fig. 6 is a perspective of a bridge employed in the chase.

Referring more in detail to the drawings, 1 indicates the body provided with a drawer 2, designed for storage purposes, and a platen 3 disposed on the top of the body, said platen having a covering 3' of felt, or 40 the like, on which the paper is placed.

On the top of body 1 is provided spaced ears 4 to which is mounted for vertical swinging movement the chase carrying frame 5. This frame is provided in the 45 lower edge portions of side frame members 5' with elongated bearings 6 in which are journaled the stub shafts 7 and 7' of chase 8. Bearings 6 are opened at their lower ends for the reception of said shafts, the latter being retained from dislodgment by the 50 resilient or spring fingers 9 which are carried by side member 5' and provided with curved seats 9' to serve as bearings for said shafts when the frame is in the inking position, 55 shown in Fig. 3. When printing or im-

pressing the paper, a solid bearing will be given the stub shafts, while in inking the type a yielding bearing is provided.

An inking pad 10 is slidably supported, in a plane above platen 3, on the spaced supports 11 secured to body 1, and is limited in its sliding movement by the upturned extensions 11' of supports 11. The pad proper is supported in a pivotal manner, in its tray, on resilient blocks 10' and 10'', the latter being 60 thicker than blocks 10' and forming the pivot for the pad as is brought out in my application for patent covering the same, filed April 21, 1913, and Serial No. 762,609, whereby to adjust itself to slight variations 65 from the horizontal of chase 8 when inking the type. In inking the type, chase 8 is permitted to yield, through its resilient mounting 9, on exerting downward pressure on frame 5, by its handle 12, whereby a thorough 70 inking is obtained. During this operation, pad 10 is caused to slide on its mounting to prevent the type from slipping over said pad and to thoroughly ink the type.

Stub shaft 7' is extended beyond its bearing 6 and secured in the apertured terminal of lever 13 by set screw 14. The opposite terminal of lever 13 is connected by link 15 to the arm 16 fastened to and projecting from body 1. Through this construction, the horizontal position of chase 8 is maintained in striking the platen and pad. The self adjustability of the pad will accommodate for slight variations from the horizontal of the chase in striking and after striking the 80 former.

The type 17 are clamped between furniture pieces 18 by clamping screw 19, the latter engaging in the threaded bore through shaft 7. Bridge pieces 20 are carried by 85 chase 8 and disposed at intervals between the furniture pieces to prevent the same from springing out under pressure from screw 19 and also to maintain an even striking face of the type. In this connection it will be noted that the furniture pieces 18 which have projecting end lugs 18', adapted to normally seat on the upper face of chase 8, as shown, are removable from the chase by a vertical or perpendicular movement while the bridge 95 pieces 20, whose end portions are matched (see Figs. 5 and 6) to straddle the adjacent walls of the chase, are not removable by such movement. Therefore the bridge pieces 20 will serve to hold furniture pieces 18 against 100 105 110

springing out of the chase when the type are held therein.

In setting the type, the covering may be removed from platen 3 whereby a solid and even surface is presented upon which the face of the type may rest before clamping the same, to obtain an even setting.

Having thus described my invention, what I claim as new, and desire to secure by 10 Letters Patent of the United States of America, is:—

1. In a press of the character described, a platen, ink supply means, a chase, yieldable means engaging the chase for engagement of the latter with one of the aforesaid elements, and other means engaging the chase for non-yielding engagement with the other of said elements.

2. In a press of the character described, 20 a platen, ink supply means, a chase adapted for engagement with the aforesaid elements, movable means supporting the chase, and yielding means adapted to engage the chase only when the latter is engaging a certain one of the first two named elements.

3. In a press of the character described, 30 a platen, ink supply means, a frame interposed therebetween, a chase carried by the frame and adapted to engage the platen and ink supply means, and yieldable means on the frame adapted to be engaged by said chase when the latter is engaging one of the first two mentioned elements and free from the chase when the latter engages the other of said first named elements.

4. In a press of the character described, a platen, an ink supply means, a frame movably mounted therebetween and provided with elongated bearings, a chase mounted 40 in the bearings of said frame and adapted for engagement with the platen and ink supply means, and yielding means adapted to engage the chase when the latter strikes a certain one of the two first named elements.

45 5. In a press of the character described, a

platen, a movably mounted ink supply means, a frame movably mounted therebetween and provided with elongated bearings, a chase mounted in the bearings of said frame and adapted for engagement 50 with the platen and ink supply means, and yielding means adapted to engage the chase when the latter strikes a certain one of the two first named elements.

6. In a press of the character described, a 55 platen, a horizontally movable ink supply means, a chase, and means swingingly supporting the chase, said chase being adapted for engaging the ink supply means which latter is capable of movement to accommodate for movement of the chase on continued swinging of the second named means.

7. In a press of the character described, 65 a platen, ink supply means, a chase, a chase-carrying frame movable between the platen and ink supply means whereby the chase may engage the same, means connected with the chase for properly disposing the latter for engaging the platen and ink supply means during movement of the frame, and 70 yielding means adapted to support the chase during engagement of the latter with one only of the first two named elements.

8. In a press of the character described, 75 a platen, a horizontally slidale ink supply means, a chase, and means swingingly and yieldingly supporting the chase for engagement with the ink supply means, the latter being slidale by the chase, as the latter yields on movement of the second means after the chase engages the ink supply means, 80 to effect a proper inking of the type in the chase.

Signed at Seattle, Washington this 15th day of April 1913.

CHARLES M. HATCHER.
